UNITED STATES PATENT OFFICE.

FRED M. HOWE, OF WELLSBORO, PENNSYLVANIA.

CAP GUN.

Application filed September 13, 1926. Serial No. 135,239.

This invention relates to sounding toys and aims to provide novel means whereby a cap of the explosive type may be exploded to cause a projectile to be thrown through 5 the air.

An important object of the invention is to provide a device of this character wherein the cap to be exploded is held within a recess formed in the projectile, the recess in 10 the projectile also affording means whereby the reduced end of the head at one end of the barrel of the device may be inserted to support the projectile on the head for firing purposes.

15 Another object of the invention is to provide a construction of this character wherein the plunger engages the head to cause the projectile to be moved against the head to explode the cap, the construction being 20 such that the plunger does not at any time contact with the cap.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawing:

Figure 1 is a side elevational view of a device constructed in accordance with the 35 invention.

Figure 2 is a longitudinal sectional view therethrough.

Figure 3 is a sectional view taken on line 3-3 of Figure 2.

40 Figure 4 is a sectional view taken on line 4-4 of Figure 2.

Figure 5 is a perspective view of the plunger employed as one of the elements of the invention.

45 Figure 6 is a sectional view through a modified form of the invention.

Figure 7 is an enlarged sectional view through the head employed in the modified form of the invention.

50 Figure 8 is a sectional view through a modified form of head and projectile.

Figure 9 is an elevational view illustrating the inner end of the projectile as shown by Figure 8.

55 Referring to the drawings in detail, the

reference character 5 designates the barrel of the device, one end of the barrel being closed by the head 6 which is secured in position by means of the rivets 7. This head is formed with a reduced end portion 8 which 60 is preferably circular in cross section and adapted to be fitted in the circular opening formed in the projectile 9.

The projectile 9 acts as a support for the cap which is exploded to accomplish the 65 purpose of the invention, the cap in the present instance being indicated by the reference character 10, and it will be seen that in the operation of the toy, the cap is positioned within the opening of the projectile 70 and the projectile positioned over the reduced end 8, in a manner as shown by Figure 2.

The plunger forming a part of the invention includes a solid portion 11 designed to 75 engage the head 6, the plunger being moved forwardly by the action of the coiled spring 12, which is positioned within the barrel 5, one end thereof engaging the member 11, while the opposite end engages the washer 80 13 positioned in the opposite end of the barrel 5.

A rod 14 forms a part of the plunger and is of a length so that one end of the rod will extend beyond one end of the barrel to 85 be gripped by the hand of the operator to retract the plunger which when released engages the head 6 with such force as to cause the projectile 9 to move towards the head, exploding the cap positioned within the projectile. It follows that the force of the explosion will cause the projectile to be thrown 90 through the air.

In the form of the invention as illustrated by sheet 2 of the drawings, the barrel is indicated by the reference character 15, one end of the barrel in this showing being closed by the head 16 that is provided with a recess to accommodate the extension 17 forming a part of the projectile 18. In this 95 form of the invention, the cap which is indicated at 19 is held within the head 16 and exploded when the plunger, to be herein-after more fully described, is forced against the head 16.

In order that the projectiles of the devices will be guided with a degree of accuracy, blades 20 are provided thereon, on opposite sides.

As illustrated the barrel 15 is connected 110

with a bow 21 which has its ends connected by means of the flexible member 22 that has connection with the plunger rod 23 and which carries the plunger 24 at its inner end.

In the latter form of the invention, the device is used as a bow and arrow, the flexible member 22 being drawn rearwardly and released, to cause the firing of the cap.

10 In the modified form of the head and projectile as shown by Figure 8, the head indicated at 25, is formed with a central opening to receive the cap 26 and the projectile which is shown at 27 is provided with a 15 circular groove to receive the portion of the head formed by the opening in the end thereof.

Like the other forms of the invention, the projectile 27 is provided with blades 28 to 20 direct the projectile in its flight.

It might be further stated that it is contemplated to construct the projectiles of a soft material such as rubber, cork or the like so that a person could not be injured if struck by the projectile.

I claim:

In a device of the character described, a barrel, a head closing one end of the barrel, an extension on the head, a projectile having an opening to accommodate the extension, said opening adapted to accommodate a cap to be engaged by the extension, a spring pressed plunger operating in the barrel and adapted to be forced against the head to explode the cap to force the projectile from the head.

In testimony that I claim the foregoing as my own, I have hereto affixed my signature.

FRED M. HOWE.
